RUBBER HEEL

Albert L. Murray, Auburn, Ind.

Application May 21, 1938, Serial No. 209,259

13 Claims. (Cl. 36—35)

This invention relates to a rubber heel structure.

The chief object of this invention is to provide in a rubber heel certain bearing areas on the surface thereof which insure coplanar contact and thereby prevent biased, cocking or tilting contact.

Another chief object of the invention is to provide in a heel of the aforesaid character a resilient cushion arrangement so associated with the coplanar contact providing means that cushioning contact is also obtained.

The chief feature of the invention consists in constructing a rubber heel and providing the same with the instrumentalities necessary to accomplish the aforesaid objects.

Other objects and features of the invention will be set forth more fully hereinafter.

The full nature of the invention will be understood from the accompanying drawing and the following description and claims.

In the drawing, Fig. 1 is a plan view of one embodiment of the invention looking at the tread face thereof.

Fig. 2 is a longitudinal central sectional view taken on line 2—2 of Fig. 1, and in the direction of the arrows.

Fig. 3 is a transverse, sectional view taken on line 3—3 of Fig. 1 and in the direction of the arrows.

Fig. 4 is a plan view of the heel and directed toward the anchoring face thereof.

In the drawing 10 indicates the body portion of a rubber heel formed of rubber material of the usual or any preferred character and having a partially elliptical periphery 11 and a forwardly inclined and arcuately outlined face 12. The face secured to the shoe includes an inclined peripheral border portion 13 and a central portion 14 provided with a face which is slightly corrugated. It is also provided with an additional hollow portion or recess 15 to which reference will be had hereinafter.

The opposite or tread face, to which the invention is primarily directed, is provided with a back abutment portion 16 which is substantially horseshoe shape, as illustrated, and is eccentrically arranged relative to the major and minor axes of the body portion, the eccentricity in a pair of heels being of opposite character.

In the present invention, this abutment of heel plate character, as it were, terminates at and is coincident with the side face 11 of the heel. This heel plate structure is integral with the body portion and may be of any suitable height and width.

There is also provided on the tread face of the

heel a plurality of buttons 17 and these are arranged in spaced relation relative to each other and in spaced relation to the various side surfaces of the heel.

Within the outline of the heel plate abutment, there also is formed in a similarly spaced relation, buttons 18. These have a height substantially that of the abutment 16 and preferably do not exceed the same. The buttons 17 have a height substantially that of the abutment. Thus, all of the tread surface contacting areas have a common height and, therefore, provide for coplanar contact. Each of the buttons 17 and 18 is provided with bore portions 19 and 20, respectively. If desired, these may be countersunk as illustrated and as indicated at 19A and 20A, respectively.

Imbedded in the body portion 10 are apertured washers 21 each having the aperture 22, the latter registering with the adjacent bore and serving to locate the body portion of the nail or other equivalent anchoring device subsequently inserted in the bore and extending thru the heel and into the shoe for anchoring the heel to the shoe. The corrugated surface 14 may also be supplied with rubber cement for cementitious anchorage of the heel to the shoe.

Centrally positioned on the tread face of the body portion is a resilient cushion structure and the same is defined by the peripheral groove 23. Herein such groove and cushion structure is shown D-shape in form. The cushion includes the portion 24 integral with the portion 10 and an exposed portion 25 of somewhat greater resilient rubber character, although homogeneously connected thereto and, therefore, integral with the body portion. The exposed face of the cushion portion is preferably of a height substantially equal to the common height previously described. Thus the coplanar contact is maintained. The exposed surfaces of the buttons 17 and 18 and the exposed surface of the cushion portion may have any desired or preferred formation which may be of ornamental character although it may also be of utilitarian character.

The portion 25 may be of different color than the body portion which usually is black, thereby being of ornamental character. The central D-shape cushion portion 24—25 registers with the recess portion 15 so that there is mutual co-operation between the body portion interposed between the cushion insert and the well face and thus the cushion is capable of compression when subjected to load. The abutment 16 by reason of the inclusion of the buttons 18 also is of non-

slipping character as compared to a smooth faced abutment.

The abutment in the use of the article, takes the greatest amount of wear so there is provided a relatively wide back bearing area and if desired and as illustrated in Fig. 1, an extended side bearing of appreciable area for wear effect. The cushion portion by reason of its resiliency and recess nestability is not subjected initially to as much wear as the buttons and the abutment but these wear in use, the cushion becomes subject to increasing wear. The resulting structure is a heel which when properly applied to the shoe insures coplanar contact and by reason of the central cushion portion secures initial resiliency contact and of non-skidding character.

It has been determined a D-shape central formation provides approximately 14% more bearing area along the axis X—X in Fig. 1 over a circular formation.

While the invention has been illustrated and described in great detail in the drawing and foregoing description, the same is to be considered as illustrative and not restrictive in character.

25 The several modifications described herein as well as others which will readily suggest themselves to persons skilled in this art, all are considered to be within the broad scope of the invention, reference being had to the appended claims.

30 The invention claimed is:

1. A rubber heel including in integral relation a main body portion, an abutment upon the tread face thereof and positioned at the back thereof, tread buttons upon the tread face and of substantially the same height as the abutment and spaced apart and from the abutment for non-rocking bearing contact, and a central cushion portion enveloped by said buttons and abutment and having a portion of its outer surface substantially coplanar with that of the buttons and abutment.

35 2. A rubber heel including a main body portion, tread buttons of substantially common height projecting from the tread face thereof and spaced from the periphery and each other but adjacent the periphery for relatively wide and non-rocking coplanar contact, and a central cushion portion enveloped by said buttons and having a surface substantially coplanar with that of the buttons.

40 3. A device as defined by claim 1, characterized by the addition of buttons formed entirely within the outline of said abutment but of a height not greater than that of the other buttons or abutment, said abutment comprising more than the abutment included buttons.

45 4. A device as defined by claim 1, character-

ized by the central cushion portion being defined by an enveloping groove, and the outer portion of the cushion portion being of material more resilient than the body portion.

5. A device as defined by claim 2, characterized by the central cushion portion being defined by an enveloping groove, and the outer portion of the cushion portion being of material more resilient than the body portion.

10 6. A device as defined by claim 1, characterized by the central cushion portion being defined by an enveloping groove, and the outer portion of the cushion portion being of material more resilient than the body portion, and the opposite face of the body portion including a cushion registering cavity for the purpose described.

15 7. A device as defined by claim 2, characterized by the central cushion portion being defined by an enveloping groove, and the outer portion of the cushion portion being of material more resilient than the body portion and the opposite face of the body portion including a cushion registering cavity for the purpose described.

20 8. A heel, as defined by claim 1, characterized by the central cushion portion being D-shape in outline.

25 9. A heel as defined by claim 2 characterized by the central cushion portion being D-shape in outline.

30 10. A device as defined by claim 1, characterized by the central cushion portion being defined by an enveloping groove, and the outer portion of the cushion portion being of material more resilient than the body portion, and the central cushion portion being D-shape in outline.

35 11. A device as defined by claim 1, characterized by the central cushion portion being defined by an enveloping groove, and the outer portion of the cushion portion being of material more resilient than the body portion, and the opposite face of the body portion including a cushion registering cavity for the purpose described, and the central cushion portion being D-shape in outline.

40 12. A rubber heel including in integral relation a main body portion, a suitable tread face of anti-slipping character adjacent the periphery thereof, and a central cushion portion within the anti-slipping face arrangement and defined by an enveloping groove, the outer portion of the cushion portion being of material more resilient than the body portion.

45 13. A rubber heel as defined by claim 12, characterized by the opposite face of the body portion, including a cushion registering cavity for the purpose described.
